SHUTTLE

Horace H. Burdett, Hopedale, Mass., assignor to
 Draper Corporation, Hopedale, Mass., a corpora-
 tion of Maine

Application December 21, 1935, Serial No. 55,651

8 Claims. (Cl. 139—217)

The present invention pertains to automatical-
 ly threading loom shuttles and has more par-
 ticular reference to such shuttles having auto-
 matically threading tension devices for applying
 5 tension to the running filling thread.

Shuttles of the type mentioned are used in
 bobbin changing looms wherever the character
 of filling thread employed or cloth being woven
 is such as to require more tension on the filling
 10 thread than is obtainable with shuttles having
 only simple threading blocks. Of the various
 types of tension devices heretofore proposed, the
 spring clamp type, so-called, is to be preferred
 from the standpoint of simplicity and ruggedness
 15 of design and also because of the uniform ten-
 sion which it provides. However, such prior
 spring clamp tension devices have been un-
 satisfactory in that they have failed to properly
 provide for tensioning of the filling during the
 first pick after the transfer to the shuttle of a
 new filling supply. More particularly, most of
 the prior tension devices would not become
 threaded at all until the second pick after filling
 replenishment, while others would usually, but
 not always, become threaded during the first pick
 but so belatedly as to nevertheless cause defec-
 tive cloth to be woven.

The present invention seeks to provide, in an
 automatically threading loom shuttle, a first pick
 20 tension device of the spring clamp type which is
 so constructed that it will, without fail, become
 threaded early in the first flight of the shuttle
 after filling replenishment. To the end men-
 tioned, I have provided a tension device com-
 prised of opposed friction members for exert-
 ing a slip-grip upon the running filling, at least
 one of the members being provided on its thread
 contacting surface with at least one ridge, groove
 or the like which extends at the proper angle to
 guide or lead the filling thread laterally of itself
 into the tension device. If so desired, the thread-
 leading conformation of the friction members
 may be confined to the entrance portion of the
 tension device, thereby providing relatively
 45 smooth friction surfaces for engaging the filling
 thread after the latter has fully threaded into
 the tension device.

Two embodiments of the invention are illus-
 50 trated on the accompanying drawings, of which:
 Fig. 1 is a plan view of a shuttle comprising the
 preferred embodiment of the invention;
 Fig. 2 is a view partly in elevation and partly
 in section taken approximately on line 2—2,
 55 Fig. 3;

Fig. 3 is a sectional view taken approximately
 on line 3—3, Fig. 1;

Fig. 4 is a view in perspective, illustrating the
 manner in which the tension device becomes
 threaded at the beginning of the first pick after
 5 filling replenishment;

Fig. 5 is a view in section taken approximately
 on line 5—5, Fig. 1, but to a larger scale and
 with the filling thread positioned as in Fig. 4;

Fig. 6 is a detail view of the preferred friction 10
 members removed from the shuttle;

Fig. 7 is a view in section taken approximately
 on line 7—7, Fig. 5; and

Fig. 8 is a detail view of a modified form of
 friction member. 15

The shuttle shown on the drawings includes a
 shuttle body 1 generally of conventional construc-
 tion, the shuttle body having a longitudinally ex-
 tending cavity 2 in which a filling carrier such
 as bobbin 3 is detachably held by any usual form 20
 of spring jaws, not shown. The shuttle is pro-
 vided with a longitudinally extending thread pas-
 sage 4 in alignment with the cavity 2, the thread
 passage being defined partly by the recess 5 in
 the shuttle body and partly by the front wall 6 25
 and rear wall 7 of the threading block 8 posi-
 tioned in said recess.

The shuttle as herein described and claimed is
 considered as though it were positioned in a
 loom and boxed on the side of the loom toward 30
 which the end of the shuttle containing the
 threading block points. Thus, the wall 9 is
 positioned substantially vertically and is the
 front wall of the shuttle, while a line extending
 longitudinally of the shuttle from the cavity 2 35
 toward the tip 10 would extend in a direction
 "outwardly" from the cavity.

The threading block may be provided with a
 guard or horn 11 which extends from the front
 wall 6 of the threading block outwardly and 40
 rearwardly over the thread passage. The horn
 11 and the contiguous part of the shuttle body
 are shown as being constructed as disclosed in
 patent to W. I. Stimpson, No. 1,985,960, granted
 Jan. 1, 1935, although such construction is neither 45
 of the present invention nor essential thereto, it
 being shown for purposes of illustration only.

The shuttle is provided with a first pick ten-
 sion device comprising a pair of friction mem-
 bers which are yieldingly pressed together for 50
 exerting a slip-grip upon the running filling.
 The tension device as shown is preferably car-
 ried by the threading block at the inner end of
 the thread passage in the latter, there being a
 rear friction member 12 and a front friction 55

member 13. The members 12 and 13 extend transversely of the filling thread and thread passage, preferably approximately vertically, as shown. The members may be slidably mounted 5 on a pin 14 near the bottom of the threading block, and the upper end of the tension device is left open to provide a thread entrance 15. The tension device is thus open in a direction laterally of the direction in which the filling 10 thread normally runs.

The particular friction members 12 and 13 shown on the drawings are formed from elongated bodies of flat steel bent into the shape more clearly shown by Figs. 5 and 6. The inner vertical edge of each of the members is beveled or flared as at 16 to facilitate passage of the filling thread without damage to the filaments. The upper or entrance ends of the members may also be curved, as shown, to facilitate the entrance of the filling thread into the tension device. Each of the friction members is provided with a horizontally extending guide lug, as 17, entering into a guide tube 18 in the threading block. Each friction member has on 25 one of its sides a friction surface 19 (Fig. 5) which except for the beveled part 16 is preferably flat and comparatively smooth.

The friction members 12 and 13 may be yieldingly pressed together in any suitable manner. 30 In the construction shown, the member 12 is backed by a surface formed on the threading block, while the front member 13 is pressed rearwardly by a spring 20 which engages between the member and an adjusting screw 21 (Fig. 3) 35 threaded into the front wall 6 of the threading block.

The principal feature of novelty of the shuttle shown resides in the provision of means operative after filling replenishment to lead the filling thread laterally of itself into the tension device. Filling replenishment takes place when the shuttle is boxed as above described, and consists of the transferring to the shuttle of a filling carrier having a full supply of filling. 45 The new filling supply has an end 7 which extends from the filling carrier longitudinally of the shuttle above the threading block to the usual fixed holder (not shown). Thereafter, the shuttle is picked in a direction away from the 50 threading block end of the shuttle which results in the filling unwinding from the filling carrier and swirling about as it unwinds. In prior shuttles, the swirling of the filling is usually relied upon to cause the filling to pass about the horn, 55 as 11, and down into the thread passage. For this reason, prior spring clamp tension devices are capable of threading only belatedly, and unreliably, as above noted.

The present invention comprehends the leading 60 of the filling thread laterally into the tension device and thread passage by utilization of the relative longitudinal movement, or feeding movement, of the filling thread, instead of relying solely upon the ballooning or swirling movement 65 of the same. I accordingly provide at least one of the friction members with at least one thread deflecting groove or ridge formed in the thread contacting surface at the entrance end of the tension device, such groove or ridge being inclined in a direction to accomplish the 70 desired result.

The particular friction members shown, 12 and 13, are each provided with a plurality of parallel, alternate ridges and grooves, for the 75 purpose mentioned, as shown more clearly by

Figs. 5 and 6. The ridges result from milling or otherwise forming a plurality of parallel grooves 22, 22 in each thread engaging surface 19. The grooves shown extend from the extreme inner edge of the surface diagonally outwardly and downwardly, and terminate short of the rearward edge of the thread engaging surface. The uppermost groove is formed on the entrance end of the thread engaging surface, and the lowermost groove terminates well above the normal path of the filling thread when the latter is fully threaded into the side delivery eye 23.

The number and size of the grooves or ridges in the friction members is not of extreme importance. I have, however, obtained best results with the construction shown, the drawings being substantially to scale.

Fig. 8 of the drawings shows a friction member which embodies the present invention in different form and which may be used in the 20 threading block above described. This form of friction member is comprised of an elongated body 24 of the same general shape as the corresponding member of the first embodiment. However, instead of being provided with a plurality of milled grooves, the thread contacting surface is ground or honed in a manner to produce a multiplicity of comparatively fine ridges and grooves extending diagonally of the member as shown at 25. This type of friction member may be preferred for use with filling thread which requires a very light tension and which is of a very delicate character, although I have obtained very good results with this member on the more common sizes and types of filling 35 thread.

It will be apparent that, very early in the first pick of the shuttle after filling replenishment, the filling thread in unwinding from the filling carrier will be thrown against the entrance end 40 of one of the friction members. Since the filling thread at the time of such contact is moving longitudinally relative to the shuttle, at considerable speed, the thread leading groove or ridge contacted by the filling will deflect the latter 45 downwardly into the tension device. The thread deflecting construction herein disclosed is so efficient that, in actual practice, the filling is pulled down into the tension device before it becomes threaded beneath the horn 11. Thus, 50 the tension device may be made to facilitate the positioning of the filling beneath the horn.

Friction members constructed in accordance with the present invention and of proper size and shape may be substituted for prior friction 55 members in existing shuttles to convert the latter into shuttles of the present invention. In other instances, the entire tension device may be applied to existing shuttles, for the same purpose. Consequently, both individual friction 60 members and complete tension devices, constructed as aforesaid, constitute articles of manufacture which I desire to claim as such.

Having fully disclosed the preferred embodiment of my invention, I claim:

1. An automatically threading loom shuttle having a cavity for a filling carrier, a longitudinally extending thread passage in alignment with said cavity, and a first pick tension device in said thread passage, said tension device being 70 comprised of opposed friction members exerting a slip-grip upon the running filling thread, one end of said tension device being open in a direction laterally of the general direction in which the filling thread normally runs, to thereby pro- 75

vide a thread entrance, the thread contacting surface of the entrance portion of at least one of said members having a series of alternate ridges and grooves which extend at an acute angle to the said direction of the filling thread in a direction to lead the filling thread laterally from said entrance into said tension device.

2. An automatically threading loom shuttle having a cavity for a filling carrier, a longitudinally extending thread passage in alignment with said cavity, and a first pick tension device in said thread passage, said tension device being comprised of opposed friction members extending transversely of the running filling thread and exerting a slip-grip upon the same, said tension device being open at one end to thereby provide a thread entrance, the thread contacting surface of the entrance portion of at least one of said members having a thread engaging ridge extending at an acute angle to the said direction of the filling thread in a direction to lead the filling thread laterally from said entrance into said tension device.

3. An automatically threading loom shuttle having a cavity for a filling carrier, a threading block having a longitudinally extending thread passage in alignment with said cavity, and a first pick tension device in said thread passage, said tension device being comprised of opposed friction members extending transversely of said thread passage and yieldingly pressed together for exerting a slip-grip upon the running filling thread, said tension device being open at one end to thereby provide a thread entrance, the thread contacting surface of the entrance portion of at least one of said members being provided with a plurality of parallel thread deflecting ridges extending at an acute angle to said members in a direction to lead a running filling thread in engagement therewith laterally into said tension device.

4. An automatically threading loom shuttle having a cavity for a filling carrier, a threading block having a longitudinally extending thread passage in alignment with said cavity, and a first pick tension device in said thread passage, said tension device being comprised of opposed friction members extending approximately vertically and yieldingly pressed together to exert a slip-grip upon the running filling thread, the upper end of said tension device being open to provide a thread entrance, the thread contacting surface of the upper part of at least one of said members being provided with a plurality of thread deflecting ridges which extend from the inner edge of

said member outwardly and downwardly along said surface to thereby lead a running filling thread in engagement therewith downwardly into said tension device.

5. In a spring clamp tension device for automatically threading loom shuttles, a pair of elongated friction members having contiguous thread engaging surfaces, spring means yieldingly pressing said members together to exert a slip-grip on a filling thread, said tension device being open at one end to provide a thread entrance, the thread engaging surface of at least one of said members having a thread deflecting groove or ridge which is positioned adjacent said entrance and which extends diagonally of said surface to thereby lead a running filling thread into said tension device.

6. In a spring clamp tension device for automatically threading loom shuttles, a pair of yieldingly opposed friction members having contacting thread engaging surfaces of elongated form, said tension device being open at one end to provide a thread entrance, the thread entrance end of the thread engaging surface of at least one of said members having a plurality of thread deflecting ridges which extend diagonally of said surface in a direction to lead a running filling thread laterally into said tension device.

7. As an article of manufacture, a friction member for a spring clamp tension device for automatically threading loom shuttles, said member being comprised of an elongated body having on one side thereof a thread engaging surface, said member and surface being curved at one end thereof for the purpose described, said member having a thread deflecting groove formed in said surface adjacent said curved end and extending generally diagonally of said surface and member in a direction to lead a running filling thread away from said curved end.

8. As an article of manufacture, a friction member for a spring clamp tension device for automatically threading loom shuttles, said member being comprised of an elongated body having on one side thereof a thread engaging surface, one end of said member being curved in a direction away from said surface to provide a thread entrance, there being a plurality of thread deflecting ridges formed in said surface at the thread entrance end thereof, said ridges extending diagonally of said surface and member in a direction to lead a running filling thread away from the said thread entrance end of the member.

HORACE H. BURDETT. 55
